W. U. ALASTALO

PHYSICAL TRAINING DEVICE

Filed Sept. 13. 1923

UNITED STATES PATENT OFFICE.

WILJO U. ALASTALO, OF NEW YORK, N. Y.

PHYSICAL-TRAINING DEVICE.

Application filed September 13, 1923. Serial No. 662,371.

To all whom it may concern:

Be it known that I, WILJO U. ALASTALO, a citizen of Finland, residing at New York, in the county of New York and State 5 of New York, have invented certain new and useful Improvements in Physical Training Devices, of which the following is a specification.

The present invention relates to physical 10 training devices and has for its object to provide a device for the development of different muscles of the legs and also of the arms, the abdomen and incidentally other parts of the body.

15 The device constituting the subject of this invention is adapted to be attached to the feet of the user and is provided with means for the attachment of hand straps or the like, so that the user, when exercising 20 with his legs, while in lying position, may not only assist the leg movements by hand, but thereby also develop the muscles of the arms and of the abdomen or other parts of his body.

25 Another object of this invention is to construct the device, so that it will be comparatively simple and inexpensive.

Other objects will appear from the detailed description of this invention.

30 In the accompanying drawing, Fig. 1 is a perspective view of my new device; Fig. 2 a top plan view thereof partly in section; Fig. 3 a cross section on line 3—3 of Fig. 2; Fig. 4 a side view of a modified construction; 35 Fig. 5 a similar view to Fig. 4 of another modification; Fig. 6 a similar view to Fig. 4 of a further modification; Fig. 7 a perspective sectional view of a further modification; Fig. 8 an illustration of the device in use and 40 Fig. 9 an elevation of the collar shown in Fig. 8.

In its simplest form, the device comprises a dumb-bell or weighted bar 10 preferably composed of detachable units, so that its 45 weight may be varied to suit the particular exercise or person making the exercise. Engaging around the intermediate cylindrical units 10' of the device, are loops 11 of leather or other suitable material formed with extensions 11' to which are attached the means 50 for supporting the dumb-bell or bar 10 on the feet of the user. In the form of construction shown in Figs. 1, 2 and 3, these means consist of two superposed straps 12, 13 of leather or the like, which are riveted or otherwise fastened to one another at their

ends, as at 14, and at intermediate parts, as at 15, to form loops 16 adapted to fit around the feet of the wearer as shown. These loops may be securely held in position on the 60 feet by means of straps 17.

Fixed to the intermediate portion on the straps 12, 13, preferably by means of a swivel joint 18, is a ring 19 or the like for the attachment of chain 20 or the like. To position the loops 11, the cylindrical sections or units 10' are formed on the circumference at the outer ends with annular grooves 10², which the loops 11 engage. The loops are held in the grooves 10² by the end sections 70 or units 10³, which constitute the weights proper and which are of larger diameter than the intermediate cylindrical sections 10', so as to form shoulders 10⁴. In use the device is applied to the feet of the user, as 75 described, and the person, while in lying position, moves his legs up and down.

When the weights are heavy or when it is desired to also use the arms and the upper part of the body in this exercise, the chain 80 20 or the like, is attached to the ring 19 and the user pulls the chain with his hands, while moving his legs.

In the aforescribed construction, the device is made to fit both feet at the same time 85 and the legs of the person using it are thereby held together and cannot be moved separately.

In the modification, according to Fig. 4, the device 21 is constructed, so that it may 90 be separated to be used one on each foot. To this end, separate straps 22 are provided, each constructed, as in the first example, of two superposed sections joined at their ends to form loops 23. Each loop is 95 attached to flaps or extensions 24 of the straps 22 adapted to engage the bar 10. The inner ends of these straps 22 may preferably be formed with means, whereby, if desired, the two devices may be joined to a single 100 piece. In the example shown, these means consist of a rigid member 25 to be detachably fixed to the inner ends of the straps 22 by bolts 26.

Instead of a rigid member, the two dumb-bells may be united by an elastic member 27, such as a rubber strap, as shown in Fig. 5. With such construction, the user will be allowed, while lifting his legs, also to move them apart and thereby perform additional 110 exercises for the development of certain other muscles of the legs.

In the modification shown in Fig. 6, separate arm straps 28 are shown attached to the loops 16 instead of the single strap or chain 20 in the first example.

5 For exercises to be performed by an invalid or to facilitate the lateral movements of the weighted legs on the floor, I found the following construction to be very advantageous. The loops 11 carrying the dumb-bells 10 are attached to metal plates or soles 29 which, by means of the loops 16, like in the first example, fit on the feet. The heel end of each sole is provided with a caster 30, so that when the person is lying on the 10 floor with the dumb-bells applied to his feet, the soles 29 will bear on the floor with their casters and thereby facilitate the movement 15 of the legs.

For the simultaneous development of the 20 muscles of the neck and for facilitating the lifting of the legs, when heavy dumb-bells are used, I may use a collar band 31, which is applied around the neck of the user. The straps or bands 28 or the chains 20 extending from the loops 16 are adapted to be attached to said collar.

The collar 31 may be formed to adjustably fit around the neck of the wearer and have suitably fixed to it rigid lateral arms 32 25 having suitable means for the attachment of the straps or chains.

I have found that with devices of the character described a number of physical exercises may be conveniently and effectively performed, whereby different muscles of the 35 legs, arms, abdomen and neck, as well as those of other parts of the body, can be quickly developed.

What I claim is:—

1. A device for physical training, comprising weighted members elastically connected together, and flexible means for the attachment of each member to a foot. 40

2. A device for physical training, comprising a weighted means, a rigid sole to 45 which said means are attached and which is formed with a roller to bear on the floor, when exercising, and flexible means for the attachment of said weighted means to the feet of the user. 50

3. A device for physical training, comprising weighted means composed of detachable units and expansibly connected together, and flexible means for the attachment of said means to the feet of the user. 55

In testimony whereof I affix my signature in presence of two witnesses.

WILJO U. ALASTALO.

Witnesses:

MAX D. DROHMAN,
JOSEPH T. McMAHON.
